UNITED STATES PATENT OFFICE

157,753

SPOTTING MACHINE

William C. Glover, Jr., Kansas City, Mo., assignor
to Bill Glover, Incorporated, a corporation of
Missouri

Application April 25, 1949, Serial No. 2,235
Term of patent 14 years

(Cl. D49—1)

To all whom it may concern:

Be it known that I, William C. Glover, Jr., a citizen of the United States, residing at Kansas City, in the county of Jackson and State of Missouri, have invented a new, original, and ornamental Design for a Spotting Machine, of which the following is a specification, reference being had to the accompanying drawing, forming a part thereof, in which

Fig. 1 of the drawing is a perspective view of a spotting machine embodying my new design,

Fig. 2 is a plan view of the spotting machine, and

Fig. 3 is a rear elevational view of the spotting machine.

I claim:

The ornamental design for a spotting machine, as shown.

WILLIAM C. GLOVER, JR.
